INVENTOR

Charles E. Overbaugh

BY *E. N. Ducker*

ATTORNEY

UNITED STATES PATENT OFFICE.

CHARLES E. OVERBAUGH, OF JERSEY CITY, NEW JERSEY.

CARTRIDGE-SHELL.

SPECIFICATION forming part of Letters Patent No. 498,856, dated June 6, 1893.

Application filed February 16, 1892. Serial No. 421,778. (No model.)

To all whom it may concern:

Be it known that I, CHARLES E. OVERBAUGH, of Jersey City, county of Hudson, and State of New Jersey, have invented a new and useful Improvement in Cartridge Shells, of which the following is a specification.

This invention relates to cartridge shells for breech loading guns and it is of the class having a paper, or similar body and a metal breech or head and the invention consists in the construction and novel arrangement of the breech and in the manner of attaching it to the body.

I will describe a cartridge shell embodying my invention and then point out the novel features in the claim.

In the accompanying drawings, Figure 1 is a longitudinal section of a cartridge, embodying my invention. Fig. 2 is a section of a metal breech in its condition before being placed on the body portion. Fig. 3 is a longitudinal section of the body portion, as it appears before the breech is attached thereto. Fig. 4 is a section showing a modified construction. Fig. 5 is an interior plan view of a breech. Fig. 6 is an outer plan view thereof. Fig. 7 is a section of another modified form of breech. Fig. 8 illustrates the breech shown in Fig. 7, as applied to the body.

Referring by letter to the drawings A designates the shell or body portion usually made of paper and suitably waterproofed if desired.

B designates the breech which may be made of metal such as aluminium or brass.

In each example of my improvement the metal breech is provided with annular jaws to engage the end of the body A.

In Fig. 2 the outer jaw b and the inner jaw b' are substantially parallel at all points of the inner surfaces.

Fig. 1 shows the breech B attached to the body A in the following manner. After inserting the end of the body portion between the jaws b b' as shown the jaws are forced laterally toward each other by means of any suitable tools engaging against the inner surface of the jaw b'. This compresses the material of the body and as the ends of the jaws joined to the main portion of the breech cannot be pressed together shoulders b² are formed which engage an annular bead like end b³ of the

body A so that the body cannot be easily detached from the breech.

In the example shown in Fig. 4, the breech B is provided with the integral outer jaw b, but the inner jaw is made separate therefrom and consists of a substantially cup shaped metal piece C. In this example the piece C is provided with an outwardly extending annular bead c at its base so that when the jaw b is pressed against the body material the end of the body material will be forced into an annular channel c' at the base of the jaw b, said channel being formed when the jaw is pressed inward.

In the example shown in Fig. 7 the jaw b has a longitudinally curved inner surface c² extending a short distance from its junction with the breech B. The inner jaw b' is like the jaw b' shown in Fig. 2. When the breech shown in Fig. 7 is attached to the body the inner jaw is forced outward or enlarged by a suitable tool so that it assumes the position shown in Fig. 8 firmly grasping the end of the body portion.

A shell or cartridge made in accordance with my improvement has all the advantages of a metal shell but can be made much cheaper. Its advantage over the ordinary paper shell is that its breech can be made much thinner and lighter, and the danger of pulling off the head when extracting the cartridge is very much decreased.

Having described my invention, what I claim, and desire to secure by Letters Patent, is—

In a cartridge shell the combination of a paper body, and a metal breech portion having the integral jaws movable laterally one toward the other for compressing a portion of and permanently clamping the paper body, the said paper body having an annular bead formed at its end to engage an annular shoulder of a jaw, substantially as specified.

In testimony whereof I have signed my name to this specification in the presence of two subscribing witnesses.

CHARLES E. OVERBAUGH.
